COMMON BILE DUCT PROBE

Jacob A. Glassman, 1680 Meridian Ave.,
Miami Beach, Fla.

Filed Aug. 30, 1962, Ser. No. 71,505

Term of patent 14 years

(Cl. D83—12)

FIG. 1 is a side elevational view of a common bile duct probe showing my new design, the opposite side is a mirror image of the side shown;

FIG. 2 is an end elevation thereof; the opposite end being substantially the same as the end shown except for the substitution of a female fitting; and

FIG. 3 is a transverse sectional view taken on line 3—3 of FIG. 1.

I claim:

The ornamental design for a common bile duct probe, substantially as shown and described.
